UNITED STATES PATENT OFFICE.

CHARLES KLEIN, OF BROOKLYN, NEW YORK, ASSIGNEE TO THE CASTLE BRAID COMPANY, A CORPORATION OF NEW YORK.

BRAID-MACHINE.

SPECIFICATION forming part of Letters Patent No. 787,383, dated April 18, 1905.

Application filed August 2, 1902. Serial No. 118,152.

To all whom it may concern:

Be it known that I, CHARLES KLEIN, a citizen of the United States, residing in the city of New York, in the borough of Brooklyn and State of New York, have invented certain new and useful Improvements in Braid-Machines, of which the following is a full, clear, and exact description.

This invention relates to braid-machines, the object being to provide a machine capable of fabricating a tubular braid in accordance with a process wherein the selvages of an ordinary flat braid are sewed or looped together to produce the tubular formation.

A further object of the invention is to provide a machine for making a tubular braid of the character described which after the tube is opened by the removal of the thread which joins its edges a flat braid is produced whose edges are parallel, but run in a zigzag or undulating direction.

These objects are accomplished in a braid-machine wherein the braid is formed around and upon a cylindrical spindle to which the shed leads and which contains a supplemental raceway intercepting the two ends of the main raceway for supplemental spindles, which carry threads for uniting the selvages of the braid around the cylindrical spindle to form the tube. The machine also embodies means for imparting a slight rotary or twisting motion to the spindle at predetermined intervals and to various extents in accordance with the pattern, whereby the wales formed by the braided threads or strands are deflected laterally to and fro and a tubular braid is produced in which the wales and the selvages while extending in a general longitudinal direction are given a zigzag or undulating direction, which is retained after the tube is opened and pressed out flat in the commercial form.

The invention also comprehends a device for forcing the tubular braid off the spindle as fast as it is formed, this being accomplished by "pushing" instead of "pulling," inasmuch as a pull on the braid only serves to tighten its grip on the spindle.

The details of the invention will be fully

described with reference to the accompanying drawings, in which—

Figure 1 is a plan of a portion of a braid-machine fitted with the improvements. Fig. 2 is a similar plan with the upper part of the machine, including the shed and spindles, removed. Fig. 3 is a vertical section of the machine. Fig. 4 is a side elevation thereof with parts in dotted lines and other parts removed for clearness. Figs. 5 and 6 are plans of two pattern-cams. Fig. 7 is a perspective of the tubular braid as it comes from the machine, and Fig. 8 is a plan of the same braid opened out flat and in commercial form.

The race-plate of an ordinary braid-machine is indicated by A and contains an ordinary undulating intersecting endless slot *a* for the several spindles *b*, which carry the threads or strands. These spindles are driven by the usual gears *b'*, (shown in dotted lines in Fig. 4,) and they travel back and forth through the race from one end, *a'*, to the other, *a''*. These spindles operating in the well-known manner would form an ordinary straight flat braid at the point *c*, where the threads of the shed converge. In the present instance there is arranged in the center of the machine a vertical cylindrical spindle *d*, to which the threads of the shed lead, and the race-plate is provided with a supplemental endless slot *e*, which crosses itself at *c'* and *c''* which intersects the two ends *a'* and *a''* of the main race. In this slot *e* are a number of spools *f*, which are driven by special gearing and which carry threads *f'* independent of the main shed, but lead to the central spindle *d*. The braid is formed around the spindle, its edges being brought close together and secured to each other by means of the threads *f''*, which are caused to interloop with the selvages and cross and recross each other between the same, as shown in Fig. 7, thus forming a closed tubular braid. In order to strip the tubular braid from the spindle as fast as it is made, it is necessary to push it off from below, because a pull on the braid causes its threads to grip the spindle and cling to it.

I therefore place upon the spindle immediately beneath the apex of the shed a semicir-

cular block g , which is carried upon the upper end of a push-rod g' , mounted in bearings in a bracket g^2 . A spring g^3 tends normally to hold the block in its lowermost position; but at regular intervals it is forced upward against the apex of the shed and the lower end of the tubular braid to force it off the spindle by a bell-crank lever h , pivoted at h' and operated by an eccentric h^2 and rod h^3 . The eccentric is on any suitable shaft of the machine and driven through any suitable gearing from the main source of power. The tubular braid is therefore pushed off the end of the spindle as fast as it is fabricated.

15 It is well known that certain machines have been invented for the purpose of making a tubular lace by sewing the edges of the lace together with an extra thread; but such machines do not involve the stripping apparatus 20 described herein, since the same is only necessary in the manufacture of tubular braid or other tubular fabrics whose threads are so laid as not to permit of easily pushing them from the spindle.

25 The reason for producing a tubular braid is to make possible the production of a flat braid having irregularly undulating parallel edges and whose body portions are set alternately on opposite sides of a central line. 30 This is easily accomplished in a tubular braid by twisting or oscillating the tube at such intervals and to such degrees as will produce a particular pattern of this general character. In order to give this twist to the braid, I 35 provide for partially rotating the spindle d , and the braid being tightly gripped thereon is twisted with the spindle.

Referring to Fig. 3 of the drawings, it will be seen that the lower end of the spindle d 40 carries a pinion d' , which is engaged by a rack-bar i . The rack-bar slides in bearings j, j' and carries at one end a roller i' , which bears against the periphery of a rotating cam k . This cam is driven in any suitable manner through gearing from the source of power 45 of the machine; but, as shown, it is on the same shaft as a worm-wheel l , driven by a worm l' . The rack-bar i is surrounded by a spring i^2 , which moves the wheel i' into contact with the cam. The cam is a pattern, 50 various forms of which may be used. In general it consists of a disk having one or more projections k' on its periphery, which may be spaced apart or arranged in groups in any desired manner, in accordance with the pattern 55 of braid to be produced. Fig. 5 shows a cam capable of producing a braid of the pattern shown in Figs. 7 and 8. The two offset or wave-like formations in Fig. 8 correspond to 60 the two projections k' of Fig. 5. When the machine is in motion, the projections k' of the cam and the spring i^2 cause the rack-bar to reciprocate, which imparts a corresponding rotary motion to the spindle d and the 65 tubular braid at its upper end. This diverts

the upper ends of all of the threads of the shed as well as the threads f' laterally and causes the wales of the braid to be formed temporarily in an oblique or spiral direction around the spindle, as seen in Fig. 7, which 7c formation remains permanently in the flat braid after the thread f' is removed. It is obvious that various other ways may be adopted for imparting the rotary movement to the central spindle, and consequently the invention is not limited to the particular means shown.

It is noted that the braid in its tubular form may become the commercial article and that by making the main race a endless instead of giving it the ends a', a'' a tubular braid can be formed without the aid of the threads f' . The invention therefore extends to a machine capable of producing a tubular braid with the undulating wales extending longitudinally, 8 which with different colors becomes an ornamental commercial article. The twisting of the central spindle is therefore not limited to the making of tubular braid which is to be opened and pressed flat.

Having described my invention, I claim—

1. In a braid-machine, the combination of a race-plate and spools which run therein, a central spindle around and upon which the braid is formed and means for imparting an oscillatory or twisting movement to the spindle at intervals, for the purpose described.

2. In a braid-machine, the combination of a race-plate and spools therein, of a central spindle around and upon which the braid is fabricated in tubular form, and a pusher located beneath the apex of the shed for stripping the tubular braid from the spindle.

3. In a braid-machine, a race-plate having a main race therein, spools adapted to travel back and forth from end to end in said race, a supplemental race intercepting the ends of the main race and spools adapted to travel therein, a central spindle around and upon which the braid is formed, and means for oscillating said spindle, for the purpose set forth.

4. In a braid-machine, a race-plate provided with a main race and a supplemental race intercepting the ends of the main race, spools traveling in the respective races, a central spindle around and upon which the braid is formed, and a pusher located beneath the apex of the shed and adapted to strip the braid from the spindle.

5. In a braiding-machine, the combination of a main race carrying spools for the body of the braid, a supplemental race carrying spools for binding the edges of the braid together, means for fabricating the braid in tubular form and means for twisting the braid while being fabricated.

6. In a braiding-machine, the combination of a race-plate, a main and a supplemental race therein, two sets of spools for the respective races, a central spindle to which the shed leads

and around and upon which a tubular braid is formed, means for twisting the central spindle and a pattern for determining the extent and time of the twisting, substantially as described.

7. In a braiding-machine, the combination of a race-plate, a main and a supplemental race therein, two sets of spools for the respective races, a central spindle to which the shed leads and around and upon which a tubular braid is formed, a pinion on the central spindle, a rack engaging said pinion and a rotating pattern-cam adapted to move said rack, substantially as described.

15 8. In a machine for forming a tubular braid, the combination of traveling carriers for the threads, a braid-forming mandrel or finger, a race in which the carriers are adapted to travel, the said race having terminal loops 20 adapted for the formation of a flat braid, and means for producing relative movement of rotation between the braid-forming mandrel or finger and the terminal points of the race and means for securing the edges of the flat braid 25 together for forming a tubular braid, whereby there will be formed a tubular braid having selvage edges of a general undulating or wavy form bound together.

9. In a machine for forming a tubular braid, 30 the combination of an organism constructed and arranged to produce a flat braid, the said organism comprising in its structure a braid-forming mandrel or finger and means for producing a relative movement of rotation between the mandrel or finger and other parts 35 of the machine, and means for binding the edges of the flat braid together for forming a tubular braid.

10. In a machine for forming a tubular braid, 40 the combination of means for forming a flat braid having selvage edges of a general undulating form, including a braid-forming mandrel or finger and means for rotating the same, and means operating simultaneously 45 with the braiding devices during the production of the flat braid for binding the edges of the flat braid together for forming a tubular braid.

11. In a machine adapted to form a tubular 50 braid, with undulating ribs, the combination

of a flat braider combined with a rotary guiding device for a tubular braid and means for converting the flat braid into a tubular braid during its process of formation, whereby a braid with matched wavy selvage edges is 55 formed.

12. A braiding-machine comprising in its structure a flat braider, including a device for forming guiding and twisting a braid during its process of formation, and means for binding together the edges of the flat braid while the same is being formed.

13. In a braiding-machine the combination of a flat braider, including means for forming a wavy braid having matched wavy, selvage 65 edges, and means for throwing a thread for binding together the said selvage edges when the same are being formed.

14. In a braiding organism the combination of a device for forming a braid with matched 70 wavy selvage edges, and means for binding together the said selvage edges during the process of formation of the said selvage edges.

15. In a braiding organism, the combination of a guiding-finger provided with means for 75 imparting an intermittent movement of rotation thereto, braiding devices for producing a braid having selvage edges and means operating in harmony with the braiding devices 80 for binding the selvages of the braid together.

16. In a braiding organism, the combination of braiding devices including means for producing a wavy braid having matched wavy selvages and a thread-carrier coöperating therewith, and means for imparting thereto a movement such as to interweave its thread into the 85 selvages of the braid.

17. In a braiding organism, the combination of braiding devices for producing a braid having matched, wavy selvages and a thread-carrier operating in harmony with the braiding devices to bind the selvages of the braid together.

In witness whereof I subscribe my signature 95 in presence of two witnesses.

CHARLES KLEIN.
